(57) CLAIM

The ornamental design for a flexible display unit, as shown and described.

DESCRIPTION

FIG. 1 is a perspective view of a flexible display unit, showing my new design;

FIG. 2 is a front view thereof;

FIG. 3 is a rear view thereof;

FIG. 4 is a top view thereof;

FIG. 5 is a bottom view thereof;

FIG. 6 is a left side view thereof, where the right side view is a mirror image of the left side view; and,

FIG. 7 is the left side view thereof like FIG. 6, but with the optional side cover cap removed, and again where the right side view is a mirror image of the left side view.
